(57) **CLAIM**

The ornamental design for a brace for securing spaced apart structural components, as shown and described.

DESCRIPTION

FIG. 1 is a perspective of a brace for securing spaced apart structural components;

FIG. 2 is a front elevational view thereof, the rear elevational view being a mirror image;

FIG. 3 is a right elevational view thereof, the left elevational view being a mirror image;

FIG. 4 is a top plan view thereof; and,

FIG. 5 is a bottom plan view thereof.

The brace is shown broken in FIGS. 1, 2, 4 and 5 to indicate variable length.
